INCINERATOR CONTROL

Hugh W. Ewing, Chicago, Ill.

Application October 29, 1932, Serial No. 640,215

9 Claims. (Cl. 110—18)

This invention relates to incinerators, and among other objects aims to provide improved draft control mechanism for incinerators, particularly those of the flue or flue fed type.

5 The invention may be readily understood by reference to one illustrative construction embodying the invention and shown in the accompanying drawing.

In said drawing:

10 Fig. 1 is a front elevation of an incinerator showing the damper actuating mechanism;

Fig. 2 is a detail elevation, partly in section, of a construction particularly adapted for low ceiling height construction;

15 Fig. 3 is a detail elevation of the automatic release mechanism; and

Fig. 4 is a sectional elevation of the pivoted cam element in the release mechanism.

The invention is here shown embodied in a flue fed incinerator 10 wherein waste may be delivered to the incinerator through the flue 11 through which, of course, the products of combustion also pass. In apartments and similar buildings incinerator flues may reach very sub-

20 stantial heights, and because of the necessity of providing an unobstructed passage down which the waste may freely pass, the draft up such flues may become very great. Indeed, unless some controlling means be provided, the draft is usu-

25 ally great enough to carry flaming and other fragments of waste from the combustion space inside the incinerator, out the top of the flue,—thus causing a very substantial nuisance by reason of the escape of unburned and obnoxious gases

30 and solid material. Where the waste comprises a substantial quantity of light material, such as paper, a very large portion of this material in the form of small partially burned pieces may be carried up and discharged from the flue if the charging or stoking door or doors 12 of the incinerator be opened without substantially completely interrupting the draft.

According to the present invention, the draft is interrupted by a plate 13 which in this instance is in the form of a damper mounted inside the flue on a horizontal axis 14 located closely adjacent one wall of the flue so that when the damper hangs down (see Fig. 1) it will present no obstruction to the free passage of waste. If de-

50 sired, the wall of the flue may be recessed adjacent the damper and the latter carried in the recess so as to lie substantially flush with the surface of the flue when the damper hangs down. However, in most installations recessing of the flue for this purpose is a refinement which is not

necessary. In the present instance the damper plate is mounted on a horizontal shaft which extends into and preferably across the flue to a bearing in the opposite wall, and has a projection 15 of non-circular section on the exterior of the flue. The damper is preferably wider than the flue in the dimension perpendicular to its axis so that it closes the flue when in an inclined position as indicated at 16 and before it assumes a horizontal position. To allow a slight draft up the flue even when the damper is closed (so as to avoid the issuance of smoke from the open incinerator door) the damper plate is preferably slightly shorter than the dimension of the flue parallel to the damper axis. In ordinary installations a sufficient draft is maintained for the aforesaid purpose if the damper plate be an inch shorter than the flue depth. The damper plate 13 and its shaft and supporting structure are made amply heavy and strong both to carry and resist damage from heavy waste which may be thrown down upon it during the short intervals when it may be closed.

20 The pivoting of the damper along one edge to avoid the presentation of any obstruction in the flue involves the exercise of a substantial force in closing the damper,—the damper plate being of substantial thickness and offering a very substantial resistance to movement out of its vertical position. To assist in closing the damper, a counterbalance weight 17 is connected to the exterior portion 15 of the damper shaft by means of a counterbalance arm 18. The latter is held against rotation relative to the shaft by reason of the non-circular cross section of the shaft. 30 The counterbalance weight assumes substantially the position indicated at 19 (Fig. 1) when the damper is in closed position. The arm 18 is preferably mounted on the damper shaft relative to the damper in such position that when the damper is open the center of gravity of the weight lies slightly beyond the upper dead center of the shaft and therefore tends to hold the damper in open position against the wall of the flue (see Fig. 1). This is particularly advantageous in constructions of this sort, for if the lower edge of the damper extended substantially out into the flue, the metal would be substantially burned in a short time by the hot flames from the incinerator.

40 The damper is of course sufficiently underbalanced so that it will open readily by gravity. To protect the brick work or other lining of the flue against damage through blows struck it by the opening of the damper, a cushioning device in 45

50 55

the form of a hydraulic check or dash-pot 20 is advantageously interposed. As here shown the piston of the check is pivotally connected by rod 21 to the damper operating arm 22 which is also connected with the non-circular extremity 15 of the damper shaft. The lower end of the dash-pot is pivotally connected at 23 to some portion of the exterior frame work of the incinerator. The hydraulic check is of course adjusted to retard the movement of the damper sufficiently so that the latter does not strike forcibly against the wall of the flue.

The damper operating mechanism is advantageously designed not only to provide for the closing of the damper upon the opening of the incinerator door (for the purpose of stoking or charging) but to insure its complete closing regardless of the extent to which the incinerator door may be opened. In the present instance such operating mechanism is also arranged automatically to open the damper upon closing of the incinerator door. Thus the creation of a draft which would carry out solid particles from the incinerator is avoided and opening of the damper upon the closing of the door is likewise assured.

The foregoing mechanism is typified by a damper operating rod 24 pivotally connected at 25 to the damper operating arm 22 and extending downwardly across the front of the door when the damper is open. As here shown, where double incinerator doors are provided, the extremity 26 of the rod extends across the juncture of such doors to prevent opening of either of the doors until the rod has been moved to clear the doors and therefore close the damper. The closing of the damper is effected by moving the rod longitudinally upward until the damper assumes the closed position indicated at 16 at which point the rod is engaged by a latch which holds the damper closed. In this instance the latch comprises a plate 27 having an elongated slot 28 through which the rod 24 passes, and a projection 29 on the bar (in the form of a notch) which engages the plate 27 at one end of the slot 28. Until the bar is moved longitudinally to engage the latch, the damper will not remain in position but will swing open by gravity. However when so engaged, the bar has been elevated sufficiently to clear the incinerator door and permit it to be opened.

The bar is automatically released on the closing of the door by a tripping finger 30 carried by the door in a position to engage the bar and cam it laterally in slot 28 until it is released from the latch plate. The cam face on the bar is in this instance provided by a cam member 31 hinged at 32 to the lower end of bar 24 and having a surface to be engaged by the tripping finger 30. Adjacent its hinge the cam member is provided with a stop face 33 which engages the rod and limits the hinging movement to one direction only. This permits the tripping finger 30 to move outwardly (on opening the door) without releasing the damper, since the cam member hinges outwardly. On the closing movement of the door, the tripping finger 30 engages the outer face of the cam member, and since the latter cannot hinge inwardly, it is cammed laterally to release the damper. The lower extremity of the cam member is preferably provided with beveled cam surface 34 to facilitate the lateral camming action of the tripping finger.

It is apparent from the foregoing that the incinerator door cannot be opened unless the damper be completely closed before any open-

ing movement of the door (whether partial or full) occurs. Opening the door on only a partial closing of the damper, is not possible.

In Fig. 2 is illustrated a means for accommodating the aforesaid mechanism to buildings having a low ceiling height in the room where the incinerator is located. In this construction the lower end 35 of the flue is so closely adjacent the ceiling 36 that the damper shaft 37 and a portion of the damper itself lies above the ceiling. To connect the damper and its shaft to the operating mechanism (which is preferably located sufficiently below the ceiling to provide clearance for the counterweight 19), an arm 38 is connected to the damper shaft inside the flue (the shaft having a non-circular portion to prevent rotation of the arm relative to the damper). Arm 38 is connected to operating arm 22 by means of a link 39 whose lower end is pivotally connected to an auxiliary arm 40 inside the flue. The latter arm is non-rotatably connected to the shaft 41 which passes through the incinerator wall and carries on its outer end the operating arm 22 to which the damper operating mechanism is connected as illustrated in Fig. 1. By this means it is possible to locate the damper in its proper position inside the flue (independently of the ceiling height) and sufficiently far from the flue entrance so that there will be no burning of the metal of the damper or other associated parts.

Obviously the invention is not limited to the details of the illustrative construction since these may be variously modified. Moreover it is not indispensable that all features of the invention be used conjointly since various features may be used to advantage in different combinations and sub-combinations.

Having described my invention, I claim:

1. The combination with a flue fed incinerator having a door and a charging flue, of a damper plate adapted substantially to close the incinerator flue and pivotally supported on an axis at one side of the flue so that the damper when open will hang closely adjacent to one wall of the flue and leave the latter unobstructed for the passage of waste, said damper being located in the flue above the ceiling of the room in which the incinerator is located, a shaft passing through the incinerator wall to the exterior at a point below the ceiling, a damper operating arm extending down inside the flue and operatively connected to said shaft, and damper actuating mechanism connected with said shaft and associated with the incinerator door to insure closing of the damper on opening of the door.

2. The combination with a flue fed incinerator having a door and a charging flue, of a damper plate adapted substantially to close the incinerator flue and pivotally supported on an axis at one side of the flue so that the damper when open will hang closely adjacent to one wall of the flue and leave the latter unobstructed for the passage of waste, damper actuating means associated with the incinerator door to insure substantially complete closure of said damper upon opening of the door thereby to prevent strong drafts through a partly opened door, and a counterweight associated with said damper to assist in closing the damper, said counterweight being such as to permit the damper to swing by gravity to open position when released from closed position.

3. The combination with a flue fed incinerator having a door and a charging flue, of a damper plate adapted substantially to close the incin-

erator flue and pivotally supported on an axis at one side of the flue so that the damper when open will hang closely adjacent to one wall of the flue and leave the latter unobstructed for the passage of waste, damper actuating means associated with the incinerator door to insure substantially complete closure of said damper upon opening of the door thereby to prevent strong drafts through a partly opened door, and a counterweight associated with the damper and movable about an axis on the opening and closing of the damper to counterbalance the weight of the latter, said counterweight being arranged to pass slightly beyond dead center on the opening of the damper to hold the latter in open position.

4. The combination with a flue fed incinerator having a door and a charging flue, of a damper plate adapted substantially to close the incinerator flue and pivotally supported on an axis at one side of the flue so that the damper when open will hang closely adjacent to one wall of the flue and leave the latter unobstructed for the passage of waste, damper actuating means associated with the incinerator door to insure substantially complete closure of said damper upon opening of the door thereby to prevent strong drafts entering the door when partially opened, and means for releasing said damper on closing the door.

5. The combination with a flue fed incinerator having a door and a charging flue, of a damper plate adapted substantially to close the incinerator flue and pivotally supported on an axis at one side of said flue so that the damper when open will hang closely adjacent to one wall of the flue and leave the latter unobstructed for the passage of waste, a damper actuating bar adapted to project in front of the incinerator door when the damper is open to interfere with the opening of the door unless the damper be closed, means for holding the bar in damper closed position, said bar being movable to clear the door to close the damper and permit the opening of the door, and cam means engaged by the closing of the door to release said bar from the holding means to permit the damper to open, said cam means being arranged to allow the door to open freely when the damper is in closed position.

6. The combination with a flue fed incinerator having a door and a charging flue, of a damper plate adapted substantially to close the incinerator flue and pivotally supported on an axis at one side of the flue so that the damper when open will hang closely adjacent to one wall of the flue and leave the latter unobstructed for the passage of waste, a damper actuating bar adapted to project in front of the incinerator door when the damper is open to interfere with the opening of the door unless the damper is first closed, said bar being movable to clear the door to close the damper and permit the opening of the door, and releasable means for holding said bar in damper closed position and adapted to be released automatically on the closing of the door to allow the damper to open.

7. The combination with a flue fed incinerator

having a door and a charging flue, of a damper plate adapted substantially to close the incinerator flue and pivotally supported on an axis at one side of the flue so that the damper when open will hang closely adjacent to one wall of the flue and leave the latter unobstructed for the passage of waste, a damper actuating bar adapted to project in front of the incinerator door when the damper is open to interfere with the opening of the door unless the damper is first closed, said bar being movable to clear the door to close the damper and permit the opening of the door, and means for holding said bar in damper closed position.

8. A flue fed incinerator of the character described comprising in combination a charging door, a flue serving both as a smoke flue and for feeding refuse to the incinerator, a damper plate in said flue adapted substantially to close the incinerator flue and pivotally supported adjacent one edge on an axis at one side of the flue so that the damper will swing open by gravity when released and when open will hang closely adjacent a wall of the flue to leave the latter unobstructed for the passage of refuse, said damper having substantial weight and being adapted to support a load of refuse thereon, damper actuating means for swinging and holding the damper across the flue so that the same may be closed when the door is opened to prevent strong drafts from entering through the door and carrying refuse up the flue, said means being releasable to allow the damper to swing open by gravity, and an automatic brake connected with the damper for retarding the opening motion of the damper and preventing the damper plate from striking the said wall of the flue with full force when released to swing open.

9. A flue fed incinerator of the character described comprising in combination a charging door, a flue serving both as a smoke flue and for feeding refuse to the incinerator, a damper plate in said flue adapted substantially to close the incinerator flue and pivotally supported adjacent one edge on an axis at one side of the flue so that the damper will swing open by gravity when released and when open will hang closely adjacent a wall of the flue to leave the latter unobstructed for the passage of refuse, said damper having substantial weight and being adapted to support a load of refuse thereon, a counterweight associated with said damper to assist in closing the damper, said counterweight being such as to permit the damper to swing by gravity to open position when released from closed position, damper operating mechanism for swinging said damper across the flue so that the same may be closed when the door is opened to prevent strong drafts from entering through the door and carrying refuse up the flue, and means for holding said damper in closed position, said means being releasable to permit the damper to swing by gravity to open position from closed position after the closing of the door.

HUGH W. EWING. 65
